UNITED STATES PATENT OFFICE

2,088,952

INKWELL

James D. Goble, Los Angeles, Calif.

Application February 5, 1936, Serial No. 62,455

22 Claims. (Cl. 120—61)

My invention relates to an ink well of a type in which the pen is immersed and retains ink of a practically constant depth, this well being readily refilled by a downward thrust of the pen when inserted in the ink well, as such type of ink well is illustrated in my prior Patent No. 2,062,022, issued November 24, 1936.

In my present invention I present a number of improvements or further developments of the device of my prior application, one of which resides in an improved construction for maintaining the ink in a supply reservoir from contamination with the air or evaporation into the air by a more complete closure of the reservoir. Other improvements relate to the structure of the pump, the manner of mounting the pump barrel, and the plunger operated by the pen, which plunger has the ink well or pocket in which the pen is dipped.

Certain objects and features of my invention in regard to the pump construction are in a pump barrel supported with its lower end extending into the ink reservoir, the axis of the barrel being preferably inclined to the horizontal, and in which the barrel has an intake port for flow of ink from the reservoir to the bottom portion of the barrel. This port has a check valve adjacent thereto to prevent ink being forced downwardly through the port after an inflow from the reservoir. In my present construction a spring seats on the bottom of the pump barrel and normally maintains the plunger in its elevated position. Thus after the plunger has been depressed by a pen the spring forces it upwardly, causing a flow of ink into the lower part of the pump barrel.

Another feature of improvement in my invention consists in providing a transfer compartment for ink in the lower part of the plunger, which plunger is provided with a port communicating with the ink chamber in the bottom of the barrel. In this case, a check valve is used to restrain back flow of ink from the compartment of the plunger to the chamber in the lower part of the barrel.

A further improvement consists of an ink well constructed in the upper part of the plunger, there being an opening for insertion of the pen, and the plunger has ports in the form of slits leading to an annular space between a portion of the plunger and the upper part of the pump barrel. In order to fill this space with ink, openings or ports are provided in the pump barrel communicating from the transfer compartment to the annular space, thus allowing flow of ink

from the reservoir to such annular space, and thence through the slit-like ports to the ink well.

In my present invention I provide overflow openings from the upper part of the pump barrel to the reservoir for return of surplus ink. In addition, the stand has a recess in which the upper part of the pump barrel operates and from this recess there is a drain opening to the reservoir.

My invention is illustrated in connection with 10 the accompanying drawing, in which

Figure 1 is an elevation partly broken away, showing the pump with the pump plunger in its depressed position for filling the ink well with ink; 15

Figure 2 is a vertical section showing the pump with the pump plunger in its elevated position, and the remaining portion of the stand in vertical section; and

Figure 3 is a cross-section through the pump 20 on the line 3—3 of Figure 2 in the direction of the arrows.

In my invention I employ a spherical or ball-shaped stand 11, this particular shape being used for the sake of symmetry and artistic appearance. 25 The stand has a lower or base portion 12 and rests on a metal pedestal 13, the pedestal being on an ornamental base plate 14, there being a screw 15 attaching the base plate, the pedestal and the base portion of the stand. The stand 30 has an annular rim 16 with a shoulder 17. The cap or cover portion 19 of the stand has a lower peripheral portion 20 fitting outside of the rim 16 and contacting an ornamental metal ring 21 which is fitted on the shoulder 17 outside of 35 the rim 16.

The ink reservoir 25 is formed by a cylinder 26 extending upwardly from the base 12, and by the portion of the base between the lower ends 27 of this cylinder. The cylinder terminates in 40 an upper edge 28 at right angles to the axis of the reservoir cylinder. This provides the upper part 29 of the cylinder which has a tight sliding fit inside of the downturned rim 30 formed integral with the cap or cover part 19 of the stand. 45

In order to provide sufficient material for the screw 15 to engage, an internal boss 31 is formed at the lower part of the stand.

A recess 35 is formed in the cover or cap 19 by having an inwardly extending cylindrical wall 36, thus providing a circular opening 37 in the cap. The lower part of this wall is formed with a substantially internal threaded ring 38. The pump barrel designated by the assembly numeral 45 has a cylindrical side wall 46 externally threaded 55

at its upper end to engage the threaded ring 33. At the bottom 47 of the barrel there is an intake port 48 leading to an ink chamber 49. This chamber is defined by a conical check valve seat surface 50 leading to the port, and an inside cylindrical surface 51 of the barrel. A stop screw 52 is threaded through the wall of the pump barrel and located preferably on its upper side so that it will be above the level of the ink in the 5 reservoir 25. The barrel also has a series of 10 overflow holes 53 to be located above the level of ink in the reservoir and preferably immediately below the ring 38 at the bottom of the inturned cylindrical wall 36 of the cap. The pump plunger designated by the assembly numeral 60 has a lower cylindrical bearing end 61 sliding on the inside surface 51 of the barrel. Above this the plunger is reduced in diameter leaving an annular 15 passage 62 between the slightly tapered outer wall 63 of the plunger and the inside of the cylinder of the pump barrel. This construction develops a shoulder 64 which is engaged by the stop screw 52. The plunger is urged upwardly by a coil compression spring 65 bearing against 20 the check valve seat surface 50 and the lower end of the pump plunger. A lower ball check valve 66 is confined by the spring as if in a cage, and forms a check closure for the port 48 at the bottom of the pump barrel. An upper check valve 25 70 is constructed by having a sleeve 71 fitted in the lower end of the pump plunger, this having a port 72 and a cone-shaped seating surface 73 on which rests a second ball check valve 74. The port 72 leads to a transfer compartment 75 defined at its upper end by the transverse partition 76. An opening or lateral drain port 77 through the wall of the pump plunger leads from the transfer compartment to the annular space 62. 30

40 The ink well 80 is located in the upper portion of the pump plunger, being defined by the partition 76 at the bottom and the inside walls of the pump plunger. A flared mouth 81 may form somewhat of a guide in inserting the pen in the ink well. There are a plurality of slit-like openings or feeding ports 82 cut through the wall of the pump plunger above the partition 76 to provide for the filling of the ink well with ink in the manner hereunder detailed. These 45 feeding ports when the plunger is in its uppermost position, should be below the bottom of the recess 35; that is, they should not be above the upper edge of the pump barrel, so that any surplus ink displaced by inserting a pen will flow 50 out of these ports and into the annular space 62. However, should any ink spill into the recess 35, it will pass through a drain opening 83 to the 55 ink reservoir.

60 The manner of operation and functioning of my invention is substantially as follows: In order to fill the reservoir 25 with ink the cover cap 19 if desired may be removed from the base portion 12 of the stand. Of course this will remove the whole of the pump including the pump barrel 65 and the pump plunger which has the ink well therein. Then ink may be poured into the cylinder of the reservoir, care being taken that there is not an excessive amount of ink, so that the insertion of the lower portion of the pump barrel 70 into a reservoir would cause a sufficient displacement to overflow the ink over the upper edge 28 of the reservoir. However, an alternative way of replenishing the ink in the reservoir is to remove the pen from the ink well and while the 75 pump plunger is either elevated or depressed

pour ink into the ink well. This will then run through the ports 82 of the plunger and through the ports 53 of the barrel into the reservoir. Again, if desired ink may be poured directly into the recess 35 and drained directly into the drain opening 83 into the reservoir. 5

When the pump plunger is in its uppermost position shown in Figure 2 ink will flow from the reservoir through the port 66 into the ink compartment 49 and also will flow upwardly 10 through the port 72 into the transfer compartment and fill such compartment to the level of the ink in the reservoir. When a pen is inserted in the ink well the lower end of the open handle engages the flared mouth 81 of the plunger so that this may be depressed. In such action the lower check valve 66 becomes seated due to the pressure on the ink in the compartment 49, such ink flowing upwardly through the port 72 displacing the upper check valve 74 and supplying 15 more ink into the transfer chamber 75 than this has capacity to hold. Ink thus flows through the port 77 into the annular space 62 filling this space up to the overflow ports 53. But when the pump plunger is depressed as 20 shown in Figure 1, the slit-like ports 82 are below the overflow openings or ports 53, at least on the lower side of the plunger. Hence, ink flows from the annular chamber 62 into the ink well 80, the ink forming on a level with the port 25 on the lowest side. Manifestly, any surplus ink over and above that which may be held in the ink well drains downwardly through the overflow ports 53 to the reservoir. Then when the 30 pen is removed or depressing pressure of the 35 pen on the plunger released, the plunger rises to the lifted position of Figure 2, this action causing the compartment 75 in the bottom of the plunger to fill with ink and the ball 74 to become 40 more or less seated, preventing outflow of ink from the transfer compartment 75. As the plunger rises, the ink dropped in the annular space 62 drains out of the drain ports 53. It is 45 preferably to make the surface 63 tapered so the annular chamber is more restricted at the top than at the bottom. Manifestly, if any ink spills in the recess 35, it drains through the drain port 83 to the reservoir.

Various changes may be made in the details 50 of construction without departing from the spirit or scope of the invention as defined by the appended claims.

I claim:

1. In a device as described, the combination of 55 a structure having an ink reservoir, a pump barrel mounted thereon in a fixed position and having an intake port at the bottom, a plunger slideable in the barrel and having a transfer compartment with a port leading to the interior of the barrel, the upper part of the plunger having a mouth with an ink well therebelow, and means for flowing ink from the transfer compartment of the plunger to the ink well on operation of the plunger. 60

2. In a device as described, a structure having 65 an ink reservoir, a pump having a pump barrel and a plunger, means to normally maintain the plunger elevated, thereby providing an ink compartment in the lower part of the barrel, the barrel having a port communicating between the 70 reservoir and said compartment, the pump barrel having an ink transfer compartment, an open mouth at the top, and an ink well, there being a port communicating from the transfer compartment to the compartment in the lower part of 75

the barrel, and means to flow ink from the transfer compartment to the ink well on depression of the plunger.

3. In a device as described, the combination of a stand having an ink reservoir, a pump having a pump barrel and a plunger, means to hold the barrel in a fixed relation to the reservoir, the pump plunger having an ink transfer compartment adjacent its lower end, and having a mouth at the upper end, and an ink well below the mouth, there being an ink chamber in the barrel below the plunger when the plunger is lifted, and a port communicating with said chamber, the plunger having a second port communicating between the chamber of the barrel and the transfer compartment, there being a passage from the transfer compartment to the ink well whereby on depression of the plunger in the barrel ink is forced through the transfer compartment in said passage to the ink well.

4. In a device as described in claim 3, the said passage comprising an annular space between the barrel and the plunger with a port connecting from said space to the transfer compartment, and second ports connecting from said space to the ink well.

5. In a device as described in claim 3, the ink well portion of the plunger having an overflow port for return of excess ink to the reservoir, the upper part of the stand having a recess in which the upper part of the plunger extends, and a drain opening from said recess to the ink reservoir.

6. In a device as described, the combination of a stand having an ink reservoir, a pump having a pump barrel and a plunger, means to hold the barrel in a fixed relation to the reservoir, the pump plunger having a bearing end operating in the barrel and a reduced upper section forming an annular passage between the upper portion of the plunger and the barrel, the plunger having an open mouth at the top with an ink well therebelow and ports through the plunger communicating between the annular space and the inkwell, a spring interengaging the bottom of the barrel and the lower end of the plunger to normally maintain the plunger elevated, means operative on the depression of the plunger to force ink from the reservoir to the annular space and thence from such space to the inkwell.

7. In a device as claimed in claim 6, the means to force the ink from the reservoir to the annular space comprising a port having a valve in the lower part of the barrel communicating with the ink chamber in the bottom of the barrel, a second port having a check valve leading from the bottom of the plunger to the said ink chamber, there being an ink transfer compartment in the plunger separated from the inkwell and a port in the plunger from the transfer compartment to the said annular space.

8. In a device as described, the combination of a stand having an ink reservoir in its lower portion, a pump barrel held in a fixed position in the stand with its lower portion immersed in the ink of the reservoir, a pump plunger slidably mounted in the barrel and having a bearing end with a sliding fit, a spring reacting between the barrel and the plunger normally maintaining the plunger elevated and thereby forming an ink chamber in the lower part of the barrel, a first port having a first check valve in the barrel communicating between the ink reservoir and the ink chamber, the plunger having an upper portion reduced in diameter forming an annular space

between the plunger and the barrel, the upper end of the plunger having an open mouth and an inkwell therebelow, a port in the plunger communicating between the inkwell and the annular space, and an operative means on depression of the plunger to transfer ink from the ink chamber of the barrel to the said annular space whereby ink may flow from said space to the inkwell.

9. In a device as claimed in claim 8, the said operative means to transfer ink comprising a partition in the plunger forming the bottom of the ink well, a closure means for the bottom of the plunger forming a transfer compartment between the partition, the closure element and the walls of the plunger, there being a port with a check valve communicating between the ink chamber of the barrel and the transfer compartment of the plunger, and a port in the plunger leading from the transfer compartment to the said annular space.

10. In a device as claimed in claim 8, the upper portion of the stand having a recess with the pump barrel attached thereto and a drain opening from said recess to the reservoir to return overflow ink from the annular space in the ink well to the reservoir.

11. In a device as described, the combination of a stand having an ink reservoir at the bottom, a pump barrel secured to the stand and held in a fixed position with its lower end in the inkwell, a plunger having a bearing end slideable in the barrel, a spring between the bottom of the barrel and the bottom of the plunger normally holding the plunger elevated, there being an ink chamber in the barrel between the bottom of the plunger and the bottom of the barrel, the barrel having a first port with a first check valve communicating between the ink chamber and the ink reservoir, the plunger having a transverse partition and an ink transfer chamber below the partition and an inkwell above the partition, a second port with a second check valve in the bottom of the plunger communicating between the ink chamber of the barrel and the ink compartment of the plunger, the plunger having an open mouth communicating with the inkwell for insertion of a pen, there being an annular space between the upper portion of the plunger and the pump barrel, the plunger having a third port communicating between the transfer chamber and the said space, and a fourth port communicating between said space and the inkwell whereby on depression of the plunger ink flows through said space to the inkwell.

12. In a device as claimed in claim 11, the stand having a recess at the top with the barrel located at the bottom of the recess, the pump barrel having a drain opening communicating from the annular space to the ink reservoir and the recess having a second drain opening communicating with the ink reservoir.

13. In a device as claimed in claim 11, the said annular space being tapered whereby when the plunger is in its uppermost position there is but little clearance between the barrel and the plunger to restrict the contact of air with the ink in said annular space.

14. In a device as claimed in claim 11, the stand having a base portion with the reservoir therein, a cover cap secured to the base of the stand and having an opening, the pump barrel being threaded in said opening whereby the ink in the reservoir is substantially out of contact with the air outside of the interior of the stand.

15. In a device as described, the combination

of a stand substantially spherical on its outside surface and having a lower or base portion and a cover or cap portion with a joint therebetween, the joint being at substantially an angle of 45° 5 with the horizontal, a structure having a cylindrical wall secured to the base, the axis of the cylinder being inclined upwardly at an angle of 45° and at right angles to the plane of the said joint, the said cylinder with the portion of the 10 base forming an ink reservoir whereby the level of ink in the reservoir may be above the lowermost portion of the said joint, the cap having an opening, a pump barrel secured to the cap at the said opening and having its lower end extending 15 into the cylinder forming the ink reservoir, a pump plunger slidably mounted in the barrel, and having an open mouth with an inkwell therebelow, and resilient means to maintain the plunger elevated, and an operative means on depression 20 of the plunger to flow ink from the reservoir into the barrel and from the barrel through part of the plunger to the inkwell.

16. In a device as claimed in claim 15, the cap having an inwardly turned cylindrical wall at the 25 opening with an internal threaded rim, and the pump barrel having a threaded connection to said rim.

17. In a device as claimed in claim 15, the cap having an inturned rim engaging the upper part 30 of the cylindrical walls forming part of the ink reservoir, thereby limiting the air in contact with the ink at the reservoir to the air above the level of the ink and below the portion of the cap inside of the said rim.

35 18. In a device as described, a stand having an ink reservoir at the bottom, a pump barrel fixedly mounted in said stand to have its lower end immersed in the reservoir, a port in the barrel communicating with the reservoir, a pump plunger 40 having an ink well at the upper part with a mouth at the top of the ink well, means normally retaining the plunger with the ink well elevated, the said plunger being adapted to be depressed by a portion of a pen holder engaging the said 45 mouth with the pen out of contact with the bottom of the ink well to thereby depress a plunger, means forming a communication from the lower portion of the pump barrel to the ink well for flow of ink to supply the said well.

19. In a device as described and claimed in claim 18, a structure forming a recess connected to the stand, the pump barrel being attached to the base of said recess, the pump plunger and the mouth extending upwardly into the said 5 recess, the said recess having a drip opening communicating with the reservoir.

20. In a device as described, the combination of a stand substantially spherical on its outside surface and having a lower or base portion and a cover or cap portion, a reservoir structure in the base, the cap having an opening with a pump barrel connected thereto, the axis of the said barrel being at substantially 45 degrees to the horizontal, the barrel having a valve communicating with the reservoir to an ink chamber above the valve, a pump plunger slidably mounted in the pump barrel, means to normally elevate the plunger, the said plunger having an ink well at its upper end with a mouth for inserting a pen, 20 such pen being adapted for depression of the plunger and means forming an ink connection between the ink chamber and the ink well, the upper portion of the plunger and the mouth thereof extending above the upper end of the 25 pump barrel.

21. In a device as described and claimed in claim 20, the said cap having a recessed structure to which the pump plunger is connected with a drip opening to the reservoir, the cap also having a connection to the reservoir structure to exclude circulating air from said reservoir.

22. In a device as described and claimed in claim 20, the cap having a recess structure with the pump barrel connected to the bottom of the 35 recess, a drip opening from the recess to the reservoir, the means forming the ink connection including an annular space between the pump barrel and the plunger, the bottom of the ink well being defined by a partition, there being an 40 ink transfer chamber therebelow, a valve communicating from the bottom of the plunger to the transfer chamber, a first port from the chamber to the annular passage, a second port from the passage to the ink well and a third port from the pump barrel to the reservoir communicating with the said annular passage for overflow of the ink from said passage to the said reservoir.

JAMES D. GOBLE.
